BED STRUCTURE

Darwin Manauer, La Grange, Ill., assignor to
 Nachman Spring-Filled Corporation, Chicago,
 Ill., a corporation of Illinois

Application January 3, 1933, Serial No. 649,758

1 Claim. (Cl. 5—21)

The present invention relates to improvements in a type of bed known as a studio couch, which is used for seating purposes during the day and is converted into or used as a bed at night, and relates more particularly to the type of bed of this particular description, which comprises two units which are adapted to be disposed side by side to form a double bed and includes a collapsible unit which is received and stored within the base 10 portion of the main unit when not in use.

The main object of the present invention is to provide a two unit bed structure of the above description, having certain characteristics and advantages which are hereinafter fully pointed out 15 and described.

In the accompanying drawings, illustrating a suitable embodiment of the invention:

Fig. 1 is a plan view of a bed structure constructed in accordance with the invention, the 20 wire fabric or other mattress supporting means being omitted from illustration.

Fig. 2 is a vertical longitudinal section of the same on the line 2—2 of Fig. 1.

Fig. 3 is a fragmentary transverse perspective 25 sectional view of the main or receiving member or unit of the structure.

Fig. 4 is a fragmentary view in elevation showing a manually operable latch employed.

Fig. 5 is a fragmentary detail perspective 30 sectional view of a caster wheel and bracket forming part of the structure.

Fig. 6 is a perspective view of an angle iron employed in connection with one of the rails of the bedstead.

35 The structure comprises the bedstead "A" which consists of side and end rails to form a rectangular box-like structure having an opening at the front, and upon the upper edge portion of which a wire fabric or other mattress support is adapted to be mounted.

In the instance illustrated, one side rail and the two end rails are composed of boards or plates of suitable material and these are of the desired height, the latter being such that when two mattresses are disposed upon the aforesaid mattress support, the total height of the unit will be such as to constitute the same a comfortable seating unit. The said side and end rails are suitably reinforced against flexing under the tension of 45 the mattress support and are supported upon caster wheels (1).

The other side rail of the bedstead consists of a bar (2) which is reinforced by means of the angle iron (3) shown in detail in Fig. 6, which is 55 equipped with end flanges (4 and 5) respectively,

suitably secured to the end rails for obvious purposes.

The bar (2) is of such height as to leave an appreciable opening below the same, and opposite the first mentioned side rail, for the reception and removal of a collapsible sleeping cot (6) such as is fully illustrated and described in my companion application filed of even date herewith, and bearing Serial No. 649,759. The 60 said sleeping cot (6) comprises the usual rectangular frame equipped with a wire fabric mattress support and which is also equipped with folding or collapsible supports (7) which are equipped with caster wheels (8) resting on the floor when said supports are folded as shown in 65 Fig. 2, so that said cot may be readily moved through the opening below the bar (2) for storage within the bedstead "A".

The first mentioned side rail of the member "A" is equipped with a suitable latch member 70 (9), shown in Figs. 3 and 4, which consists of an L-shaped lever pivotally secured at its elbow portion to the said side rail by means of the pivot pin (10) and has a short arm (11) presenting an ogee curved end portion or flange (12) so disposed and arranged that when the sleeping cot (6) is moved through the opening below the bar 75 (2) and against the first named side rail opposed to said opening, a side rail of the cot (6) will engage the said flange (12) of the latch member to 80 cause the latter to be moved to engage said flange in a well known manner. The said flange (12) is disengaged from the side rail of the cot (6) by 85 digital engagement of the longer arm of the latch (9) to move the same in an obvious manner to 90 disengaging position.

The said bedstead "A" is also equipped along 95 lower edge of the first mentioned side rail and along its end rails with angle-iron stiffening members to which L-shaped brackets (13 and 14) respectively, are secured, which are disposed so that the last mentioned side rail of the cot (6) and the end rails of said cot, will be disposed above the horizontal arms of said brackets when said cot is 100 disposed within said bedstead and is engaged with the latch (9). Hence, upon lifting the bedstead "A" for purposes of transporting the same, the said horizontal arms of the brackets will support the cot (6) and cause the latter to be carried by 105 the bedstead "A". Preferably, the brackets (14) are provided, also, with flanges (15) which are disposed within the confines of the caster wheel frames of the caster wheels (1) and are secured to the end rails of the bedstead "A" by means of 110

fastening devices (16) which also secure the of the general type to which the invention relates.
caster wheel frames in place.

Obviously, the mattress support for the bedstead "A" may be of any type desired and may constitute the lower wall of a mattress-like cushion or similar upholstery constituting a permanent and inseparable part of the bedstead. The cot (6) may carry bedding when not in use, while the mattress for said cot is disposed upon the 10 mattress or cushion of the bedstead.

It will be obvious that the bedstead "A" may be sold by dealers as a unit by itself or as part of the double bed structure including the cot (6), and that the latter may also be sold by the dealer as a 15 separate unit. A further advantage of the invention lies in its low cost of manufacture and its light weight due to the omission of more or less heavy mechanism ordinarily found in structures

I claim as my invention:

A bed structure comprising a unit consisting of a rectangular frame adapted to carry a mattress support and having its end walls and one of its side walls composed of plates, a bar parallel with the said side wall and secured to the end walls and having its upper edge flush with the upper edges of said end and side walls, there being an open space below said bar for insertion and removal of a collapsed companion unit, casters for said end walls, and Z-shaped brackets presenting inwardly projecting arms for supporting said collapsible unit, said brackets having other arms overlapping the top of the caster, and fastening devices common to said brackets and casters securing the same to said end walls.

DARWIN HANAUER.
